UNITED STATES PATENT OFFICE.

JOHN H. JONES, OF MANCHESTER, COUNTY OF LANCASTER, ENGLAND.

SASH-CORD FASTENER.

SPECIFICATION forming part of Letters Patent No. 381,018, dated April 10, 1888.

Application filed July 13, 1887. Serial No. 244,183. (No model.) Patented in England September 4, 1886, No. 11,266.

To all whom it may concern:

Be it known that I, JOHN HARROP JONES, a subject of the Queen of Great Britain, residing at Manchester, in the county of Lancaster, England, have invented Improvements 5 in Sash-Cord Fasteners, (for which I have applied for a patent in Great Britain, No. 11,266, dated September 4, 1886,) of which the following is a specification.

10 The object of this invention is to enable cords to be attached to sash-window frames much more readily than has hitherto been possible and to enable the said cords to be replaced or readjusted with great facility and accuracy 15 without any necessity for knotting the end of the cord.

Figure 1 on the annexed drawings is a vertical section taken through about the line A. B in Fig. 2 of part of a sash-stile with my invention (shown also in section) applied thereto.

20 Fig. 2 is a face view of the same, and Fig. 3 is a face view of my improved sash-cord fastener with the cover removed. Fig. 4 is a similar view to Fig. 1, but drawn on a reduced scale 25 and illustrating another method of attaching the cord.

I attach, preferably to the inside edge of each sash-stile *a*, Fig. 2, a small metal plate or box, *b*, in which a hole, *c*, is made for the 30 passage of the cord *d*. (See Figs. 1 and 2.) The cord also passes through a hole, *e*, bored in the sash-stile *a* and inclining upward into the ordinary groove, *a'*. This plate or box *b* is also provided with a wedge-shaped hole or 35 slot, *f*, (see Fig. 3,) below the hole *c* and having its tapering or wedge portion extending toward the hole *c*.

The cord *d* having been drawn through the stile and through the hole *c* in the plate, its 40 end is bent backward and passed through the lower open part of the wedge-shaped slot *f* and upward between the back of the plate or box *b* and the back of the recess *a'*, formed in the stile *a* for the reception of the same.

45 Upon then pulling the cord up in the direction of the arrow, Fig. 1, it will be forced up into the wedge shaped slot *f*, and will be se-

curely held therein without any necessity for knotting the end.

I would here remark that, if preferred, the 50 cord may be first drawn in through the wedge-shaped slot *f* and then doubled back through the hole *c*, as shown at the reduced view, Fig. 4; but the method first described I consider better and easier to adjust. 55

It will be evident that the cord can be lengthened or shortened at any time by drawing the loop downward into the wide part of the slot *f*, and after adjusting the cord as desired it can be firmly refixed by drawing it again in 60 the direction of the arrow. A suitable cover, *g*, is screwed or may be hinged or otherwise secured to the plate or box *b* to conceal the openings *c* and *f* and the end of the cord *d*. The cords on either side of the sash having 65 been thus attached to the window, the latter is raised and the cords passed over their respective pulleys and each brought down in its "pulley-stile," by means of the usual weight or mouse, to the level of the pocket-hole in order to be attached to the sash-weight, as usual. 70

I am aware that a sash cord fastener has been made of a band of metal with a tapering opening to receive a separate wedge-piece, around which the cord is folded. In my fastener no separate wedge-piece is necessary. The cord fastens itself in the wedge-shaped slot *f* without the use of either wedge-pieces or knots. 75

I claim as my invention— 80
The plate or box for a sash-stile provided with a hole, *c*, and below the latter a wedge-shaped hole or slot, *f*, having its tapering end extending toward the hole *c*, whereby a cord inserted in the two holes will when pulled 85 wedge itself in the slot *f*, substantially as described.

In testimony whereof I have signed my name to this specification in the presence of two subscribing witnesses.

J. H. JONES.
